UNITED STATES PATENT OFFICE.

ALFRED VICTOR DAVIS, OF ELKTON, MARYLAND.

ELECTROLYTIC CELL.

1,425,752.

Specification of Letters Patent. Patented Aug. 15, 1922.

Application filed June 7, 1921. Serial No. 475,675.

To all whom it may concern:

Be it known that I, ALFRED VICTOR DAVIS, a citizen of the United States, residing at Elkton, in the county of Cecil and State of Maryland, have invented certain new and useful Improvements in Electrolytic Cells, of which the following is a specification.

This invention relates to certain improvements in electrolytic cells. The constant electrolytic action which takes place in the ordinary chlorine cell causes the electrolyte to become impoverished of salt, whereupon the electrolysis takes place on water with the result that oxygen is given off at the anode which attacks the latter and causes its rapid deterioration. Moreover, when the electrolytic action is permitted to take place upon brine which is spent or not fully saturated, a greater voltage is required to force the necessary amperage through the electrolyte than when the latter is fully saturated and besides the electric energy that is consumed in causing the electrolysis of the water is wasted so that the efficiency of the cell is greatly lowered.

It is an object of the present invention, therefore, to provide a cell in which the electrolyte will be maintained at all times at practically a point of saturation. This is accomplished in the particular embodiment of the invention chosen for illustration by providing the cell with an electrolyte well communicating at its lower end with the space between the anode and cathode, a feed tube extending into the well to near the bottom thereof for conducting fresh brine into the well under the control of a float valve to mix with the spent brine. The electrolytic action which takes place in the anode chamber between the anode and cathode causes an upward flow of electrolyte in this chamber and a consequent downward flow in the electrolyte well so that there is a sort of thermo-siphonic action resulting in a constant circulation of the electrolyte with provision for automatically supplying fresh brine thereto in order to maintain the solution constantly at a point of substantial saturation.

In the usual type of chlorine cell, particularly the Moore and Allen type, the cathode is box-like in form and within the cathode is the anode with side and end walls confronting the side and end walls of the cathode, the space between these confront-

ing walls constituting the anode chamber in which the electrolytic action takes place. Thus substantially only the outer faces of the anode are electrically active. In a commercial size chlorine cell the carbon or graphite anode is very expensive and in a plant utilizing a number of cells it is important that a maximum output be obtained from each individual cell in order that the total number of cells and hence the total number of anodes required may be kept at a minimum. It has already been pointed out that one object of the invention is to prevent the rapid destruction of the anode by maintaining the electrolyte in the cell in a constant state of substantial saturation. Another object of the invention is to provide a cell in which the anode and cathode are so constructed and arranged that substantially the entire anode surfaces will be electrically active whereby the output of the cell will be much greater than that of a cell having an anode of similar size but in which only one face of the anode is electrically active. This object is accomplished in the embodiment of the invention shown in the drawings by providing a substantially S-shaped anode having its opposite faces confronted by similarly shaped cathodes. A further advantage of increasing the output of the individual cell by making both sides of the anode electrically active and hence reducing the total number of cells required in the plant lies in the fact that it greatly reduces the housing space required for the cells.

A further object of the invention is the provision of a cell comprising a base and sections supported by the base which are readily separable and removable from the base for cleaning purposes without removing or disturbing the anode which is also supported on the base whereby the cell may be taken apart for cleaning even when the anode is almost completely used up.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 represents a side elevation of an electrolytic cell embodying my invention.

Figure 2 is a plan view thereof.

Figure 3 is a section taken on the line 3—3 of Figure 1 looking in the direction of the arrows.

Figure 4 is a section on the line 4—4 of 5 Figure 1 looking in the direction of the arrows.

Figure 5 is a vertical sectional view taken on the line 5—5 of Figure 4 looking in the direction of the arrows.

10 Figure 6 is an end view of the cell with parts broken away.

Figure 7 is a transverse vertical sectional view taken on the line 7—7 of Figure 5 looking in the direction of the arrows.

15 Figure 8 is a plan view of the base of the cell.

Figure 9 is a side elevation of one of the sections of the cell body with parts broken away.

20 Figure 10 is a bottom plan view of the part shown in Figure 9.

Figure 11 is a plan view of the anode, and

Figure 12 is a perspective view of one of the electrolyte wells.

25 Referring to the drawings, the reference numeral 1 indicates the base of the cell which may be made of concrete or other inert material. The base is provided on its upper surface with a narrow rib 2 and 30 numerous spaced projections 3, the rib 2 and projections 3 being preferably of the same material as the base and integral therewith.

35 The sectional cell body and the anode therebetween are supported upon the rib 2 and projections 3. The cell body is made in two similar sections, each having a side wall 4 and end walls 5, the sections when fitted together with their end walls abutting forming an oblong rectangular structure. The side and end walls of each section are 40 formed of sheet metal and provided at their upper and lower edges with narrow in-turned flanges 6 and 7. The end walls 5 are also provided with vertical in-turned flanges 8. Extending inwardly from and 45 preferably integral with and of substantially the same width as the upper and lower flanges 6 and 7 are the U-shaped members 9 and 10, one directly over the other and arranged near one end of the section.

50 Fitting within the rectangular openings between the U-shaped members 9 and 10 and the flanges 6 and 7 is an electrolyte well 11. The plane of the lower U-shaped member 10 is slightly above that of the lower flange 7 and the well 11 is provided at its lower end with an out-turned flange 12 upon which the lower U-shaped member 10 rests, 55 the lower surface of the flange 12 being flush with the lower surface of the flange 7. The well is made of any material suitable for 60 withstanding the electrolyte, such as concrete or stoneware.

65 Secured to the edges of the flanges 6, 7 and

8 and the U-shaped members 9 and 10 is the cathode 13 consisting of suitable foraminous material such as slotted iron plates of known construction or wire gauze, as illustrated. Covering the inner face of the cathode is the diaphragm 14 consisting of suitable material such as asbestos paper. The space between the outer face of the cathode and the side and end walls 4 and 5 and between the cathode and the end walls 75 and inner side wall of the well forms the cathode chamber.

The two sections of the cell may be exact duplicates one of the other and are adapted to be assembled with the electrolyte well of 80 one section at one end of the cell and that of the other at the other end thereof. When the sections are so assembled there is provided an approximately S-shaped space 85 within the cell body. The correspondingly shaped anode 15 which may be of carbon or graphite is centrally located in this space, certain of the projections 3 on the base being grooved for receiving and supporting the anode slightly spaced above the base and 90 in a definite position thereon. The construction and arrangement is such that the sides of the anode are completely surrounded by the cathode. The space between the faces of the anode and cathode constitutes the anode chamber in which the electrolytic action takes place.

The top or free-board section 16 of the cell is made of concrete or other material which is inert to the action of the chlorine liquor 100 or gas and comprises side and end walls 17 and 18 and a removable cover member 19. The top section is also provided at its lower end with an out-turned peripheral flange 20. The cover member 19 is provided with 105 suitable openings to permit the passage of the upright carbon or graphite bars 21 attached to the anode and to the upper ends of which the positive lead wires of the circuit may be connected by means of a suitable bus bar. Openings are also provided in the cover member to receive the feed tubes 22 for supplying fresh brine to the electrolyte wells and the nipple 23 to which the conduit 24 is attached for conducting 110 away the chlorine gas collected in the free-board section. The free-board section on the interior thereof is provided with bridge members 25 which are arranged to rest upon the U-shaped members 9, the electrolyte 115 wells 11 projecting above the U-shaped members 9 and having their upper ends flush with the upper surfaces of the bridge members.

In the assembled relation of the parts of 125 the cell the lower flange 7 of the sectional body portion rests upon the rib 2 and the flanges 12 of the electrolyte wells upon certain of the projections 3. The flange 20 on the free-board section rests upon the 130

upper flange 6 of the cell body and overlies the side and end walls of the latter. For securing the sections of the body together a tie bolt 26 is provided at each end thereof, 5 the bolts extending transversely between the end walls 5 and the cathode 13, openings 27 being provided in the side walls 4 and flanges 8 for the passage of the bolts. For securing the cell body and free-board section 10 to the base vertical tie bolts 28 are provided which extend through the flange 20 and through the marginal portion of the base.

The porous diaphragm member 14 is overlapped upon and secured to the flanges 6, 15 7, 8, 9 and 10 of the cell body so that when the parts of the cell are assembled and the tie bolts 26 and 28 tightened the margins of the diaphragm between the flange 6 of the cell body and flange 20 of the free-board 20 section, between flange 7 of the cell body and rib 2 of the base, between the end flanges 8 of the cell body, between the bridge members 25 and the U-shaped members 9, and between the U-shaped members 10 and the 25 outturned flanges 12 of the electrolyte wells, provide pressure and liquid tight joints between all of these parts to prevent the escape of liquor or gas.

The cell body is provided at one end with 30 terminals 29 for connection of the negative lead wires of the circuit and at its opposite end with ports to which are connected conduits 30 and 31 through which to conduct away hydrogen gas and the cell effluent.

35 The sodium chloride solution is brought to the cell through suitable conduits 32 which enter the upper ends of the tubes 22. The level of the electrolyte in the cell is preferably kept above the tops of the 40 anode and the electrolyte wells, float valves 33 being provided in the tubes 22 for cooperation with the conduits 32 for automatically regulating the supply to maintain this level. The electrolyte percolates through 45 the porous diaphragm into contact with the cathode and the caustic soda and other cell effluent resulting from the reaction drops into the bottom of the cathode chamber and is conducted away through the cell effluent 50 conduits 31. The hydrogen gas which is given off at the cathode rises to the top of the cathode chamber and is conducted away through the conduits 30. The chlorine liberated on the surfaces of the anode is 55 collected in the freeboard section of the cell and conducted away through the nipple 23 and conduit 24.

60 The electrolytic action which takes place in the anode chamber causes an upward flow of the electrolyte in this chamber and a consequent downward flow in the electrolyte wells. Since the wells and the anode are spaced slightly above the base 2 by the projections 3 and since the level of the electrolyte is maintained above the tops of the

anode and wells, there is provision for a constant circulation of the electrolyte downward through the wells and through the openings between the lower edges of the wells and base and between the lower edge 70 of the anode and base into the anode chamber on opposite sides of the anode, upward through said chamber and over the tops of the anode and wells into the wells. This circulation of the electrolyte may be properly characterized as a thermo-siphonic circulation. 75

If the electrolytic action were permitted to take place without provision for replenishing the electrolyte, the latter would soon 80 become spent and the electrolysis would take place upon water with a consequent generation of oxygen gas on the faces of the anode which would attack the latter and rapidly eat it away. This is avoided and the electrolyte kept constantly at a point of substantial saturation by the provision of the feed tubes 22 and conduits 32 controlled by the float valves 33 through which fresh brine is conducted to near the bottom of the 90 wells to mix with and replenish the continuously circulating electrolyte.

The peculiar construction of the cell body makes it possible to expose a maximum area of anode surface in a given size cell and 95 to utilize practically the entire exposed surface thus greatly increasing the output of the cell over that of a cell having an anode of substantially equal surface area but having only one side of the anode electrically 100 active.

When it is desired to take the cell apart for cleaning purposes it is only necessary to remove the nuts from the ends of the tie bolts 26 and 28, lift off the free-board section, and then separate the sections of the cell body from the base by a lateral movement. The anode being supported by the grooved projections 3 need not be removed 105 nor disturbed during the disassembly of the cell so that even when the anode is almost completely used up the cell may be taken apart without danger of destroying the anode.

Having thus described my invention, what 115 I claim as new and desire to secure by Letters Patent is:

1. An electrolytic cell comprising an anode and a cathode arranged in spaced relation to provide an anode chamber therebetween, said chamber opening freely into the cell at its upper and lower ends, and means for supplying an electrolyte solution to said cell and automatically maintaining the level thereof above the upper end 120 of said chamber as the electrolytic action takes place in said chamber whereby to produce a thermo-siphonic circulation of the electrolyte upwardly in the chamber and downwardly in the cell. 125

2. An electrolytic cell comprising an anode and a cathode arranged in spaced relation to provide an anode chamber therebetween, said chamber opening freely into the cell at its upper and lower ends, and means for supplying an electrolyte solution to said cell at a point adjacent the lower end of said chamber and automatically maintaining the level thereof above the upper end of said chamber as the electrolytic action takes place in said chamber, whereby to produce a thermo-siphonic circulation of the electrolyte upwardly in said chamber and downwardly in said cell and to maintain the electrolyte in said cell at a point of substantial saturation.
3. In an electrolytic cell, an anode having a plurality of active surfaces, and a cathode so formed and arranged as to surround the anode in equi-spaced relation to all the surfaces thereof, whereby said surfaces will be equally electro-active in operation.
4. In an electrolytic cell, an anode having a plurality of transversely extending portions and a plurality of longitudinally extending portions, and a cathode extending about the several portions of the anode aforesaid whereby to form a relatively narrow and continuous chamber for the anolyte extending completely around the anode on all sides, thereby rendering all surfaces of the anode exposed to the electrolyte equally electro-active.
5. An electrolytic cell comprising an anode of zig-zag cross-section and a cathode of similar cross-section on each side thereof in spaced relation thereto.
6. An electrolytic cell comprising an anode of substantially S-shape in cross-section and a cathode of similar cross-section on each side thereof in spaced relation thereto.
7. An electrolytic cell comprising an anode and a cathode arranged on opposite sides thereof in spaced relation thereto and an electrolyte well communicating at its upper and lower ends with the upper and lower ends of the chambers on the opposite sides of the anode.
8. An electrolytic cell comprising an anode and a cathode arranged on opposite sides thereof in spaced relation thereto, an electrolyte well communicating at its upper and lower ends with the upper and lower ends of the anode chambers on the opposite sides of the anode, and means for supplying an electrolyte solution to said well at a point adjacent its lower end and automatically maintaining the level thereof above the upper ends of said well and anode chambers as the electrolytic action takes place in said chambers, whereby to produce a thermo-siphonic circulation of the electrolyte upwardly in said chambers and downwardly in said well and to maintain the electrolyte in said cell at a point of substantial saturation.
9. An electrolytic cell comprising a rectangular cell body, a substantially S-shaped anode arranged in said cell body, a similarly shaped cathode arranged on each side of said anode and in spaced relation thereto, each cathode including between a portion thereof and the corresponding side of said cell body a substantially rectangular space and an electrolyte well arranged in each of the spaces so formed and communicating at its upper and lower ends with the upper and lower ends of the chambers on opposite sides of the anode.
10. An electrolytic cell comprising a rectangular cell body, the side and end walls of said body being provided at their upper and lower edges with narrow inturned flanges, U-shaped members extending inwardly from the upper and lower flanges of each side wall, said upper and lower U-shaped members of each side wall being arranged one directly over the other, and the U-shaped members of one side wall being arranged near one end of the cell body and those of the other side wall near the opposite end thereof, a cathode attached to the edges of the inturned flanges on the end walls of the cell body and to the edges of the flanges on the side walls between the U-shaped members and the ends of the side walls and to the inner edges of the U-shaped members, said cathode enclosing a substantially S-shaped channel in said cell body, an anode arranged in said channel with its side walls spaced from said cathode, and an electrolyte well fitting in the rectangular space enclosed between the U-shaped members of each side wall and said side wall, said wells communicating at their upper and lower ends with the upper and lower ends of the chambers on opposite sides of the anode.
11. An electrolytic cell comprising a base, a cell body supported on said base and formed in two sections, each comprising a cathode member, and an anode supported on the base with the cathode members confronting and spaced from the opposite sides thereof, the sections of the cell body being separable from the base by a lateral movement without removing or disturbing the anode.
12. An electrolytic cell comprising a base, a cell body supported on said base and formed in two sections each comprising a cathode member, an anode supported on the base with the cathode members confronting and spaced from the opposite sides thereof, and a top or free-board section mounted on the top of the cell body, said free-board section and cell body sections being removable for cleaning the cell without removing or disturbing the anode.
13. An electrolytic cell comprising a horizontal base, a vertical cell body supported

on said base and divided vertically into two longitudinal sections each comprising a cathode member and an electrolyte well, and an anode supported on said base in spaced relation thereto with the cathode members confronting and spaced from the opposite sides thereof, said wells communicating at their upper and lower ends with the upper and lower ends of the anode chambers on opposite sides of the anode, a free-board section supported on said base in spaced relation thereto with the cathode members confronting and spaced from the opposite sides thereof, said wells communicating at their upper and lower ends with the upper and lower ends of the anode chambers on opposite sides of the anode, and said sections being separable from said base for cleaning the cell by a lateral movement without removing or disturbing the anode.

14. An electrolytic cell comprising a base, a cell body mounted on said base and divided vertically into two longitudinal sections each comprising a cathode member and a porous diaphragm covering the active face of the cathode member and overlapped upon the upper and lower and vertical dividing edges of said section, an anode supported on said base in spaced relation thereto with the cathode members confronting and spaced from the sides thereof, a free-board section mounted on the top of the cell body, means for securing the sections of the cell body firmly together, and means cooperating with the base and free-board section to clamp the cell body firmly therebetween, the overlapped margins of the diaphragm forming pressure tight joints between the vertical dividing edges of the cell body and between the lower edge thereof and the base and between the upper edge thereof and the free-board section.

15. An electrolytic cell comprising a base, an oblong rectangular cell body mounted on said base and having a vertical channel therein, S-shaped in cross-section and extending from top to bottom thereof, said channel extending transversely across said cell body adjacent and parallel to one end wall thereof, then adjacent and parallel to a side wall thereof to about the middle of the cell body, then transversely across the cell body, then adjacent and parallel to the opposite side wall thereof to the opposite end of the cell and then across the cell adjacent said end, a cathode member forming the side and end walls of said channel, and an anode disposed centrally in said channel.

16. An electrolytic cell comprising a horizontal base, a vertical cell body supported on said base and divided vertically into two longitudinal sections each comprising a cathode member and an electrolyte well, an anode supported on said base in spaced relation thereto with the cathode members confronting and spaced from the opposite sides

thereof, said wells communicating at their upper and lower ends with the upper and lower ends of the anode chambers on opposite sides of the anode, a free-board section supported on said base in spaced relation thereto with the cathode members confronting and spaced from the opposite sides thereof, said wells communicating at their upper and lower ends with the upper and lower ends of the anode chambers on opposite sides of the anode, and said sections being separable from said base for cleaning the cell by a lateral movement without removing or disturbing the anode.

17. An electrolytic cell comprising a base, a cell body supported on said base and comprising side and end walls formed of sheet metal, said cell body being divided vertically into two longitudinal sections each comprising a cathode member spaced from the side and end walls of the section to form a cathode chamber therebetween, an electrolyte well interposed between a portion of the cathode member and the side wall of each section and spaced therefrom to form a continuation of the cathode chamber about the walls of the well, and an anode supported upon said base in spaced relation thereto with the cathode members of the two sections confronting and spaced from the opposite sides thereof, said sections being separable from said base for cleaning by a lateral movement without removing or disturbing the anode.

18. An electrolytic cell comprising a base, a cell body supported on said base and comprising side and end walls formed of sheet metal, said cell body being divided vertically into two longitudinal sections each comprising a cathode member spaced from the side and end walls of the section to form a cathode chamber therebetween, an electrolyte well interposed between a portion of the cathode member and the side wall of each section and spaced therefrom to form a continuation of the cathode chamber about the walls of the well, an anode supported on said base in spaced relation thereto with the cathode members of the two sections confronting and spaced from the opposite sides thereof, current conducting members extending vertically from said anode, a free-board section supported on said cell body and having openings for the passage of said conducting members, and a feed tube for electrolyte solution extending into each well through the top of said free-board section and terminating near the bottom of the well, each section of said cell body being provided with a negative terminal and an outlet for cell effluent and an outlet for hydrogen gas.

In testimony whereof I affix my signature.

ALFRED VICTOR DAVIS.
